METHOD FOR PRODUCING METALLIC WHEELS

John T. Trumble, Detroit, Mich.

Application September 10, 1932, Serial No. 632,595

15 Claims. (Cl. 29—159.03)

The present invention relates to a method for producing metallic wheels and more particularly to a method for producing a unitary metallic spoke spider for wheels. The present application is a continuation in part of my earlier application, Serial Number 582,286, filed December 21, 1931.

The principal object of the present invention is the provision of a method for producing a wheel spoke spider wherein a plurality of tubular spoke members are pressed out of a strip of sheet metal and the strip bent into hoop formation with the spoke members extending radially therefrom.

Another object of the invention is the provision of a method for producing a wheel spoke spider wherein a plurality of connected spokes are so spaced apart that the diameter of the wheel embodying the said spokes may be varied one unit of length by adding or eliminating one spoke in the spider formation.

The exact nature and specific objects of the invention will more fully appear in the following description taken in connection with the accompanying drawings, in which:

Figure I is a plan view of a blank strip of metal utilized for producing a spoke spider in accordance with the present invention.

Figure II is a plan view of the strip shown in Figure I after being prepared for the first die drawing operation.

Figure III is a sectional view illustrating the various die drawing operations performed upon the strip shown in Figures I and II.

Figure IV is a top plan view of the structure illustrated in Figure III.

Figure V is a side view in elevation of a complete spoke spider produced in accordance with the present invention.

Figure VI is a partial cross sectional view of a completed wheel embodying the spoke spider shown in Figure V, and

Figure VII is a partial side view in elevation of the wheel shown in Figure VI.

The spoke spider 10 illustrated in Figure V comprises a plurality of radially extending hollow spoke members 21 closed at their outer extremities and all integrally connected at their base to a metallic strip 12 which is secured in the hoop formation shown by welding the opposite extremities thereof together along the line 13. Any other means desired may be utilized for securing the strip 12 in the desired formation.

In accordance with the preferred method of producing the spoke spider 10, a strip of metal 12

of suitable length, width and thickness is cut out along each of its opposite sides as indicated at 14 in Figure II to provide scallops. The strip 12 as illustrated in Figures I and II is of a suitable size from which to form the spoke spider 10 having eight spoke members as indicated in Figure V. After the strip of metal 12 has been scalloped as just described, it is fed into a die drawing machine, not shown, adapted to successively draw eight protuberances 15 from the area indicated 10 by the dotted lines 11 in Figure II. The protuberances 15 are preferably drawn one at a time since metal is drawn from all sides in forming these protuberances. Laterally movable dies 15 may be used, however, whereby all of the protuberances 15 are drawn simultaneously. It will be observed that the areas defined by the dotted lines 11, from which the protuberances 15 are drawn, are located midway between pairs of the cut out portions 14 and in the center of the 20 scalloped portions on opposite sides of the strip 12. Where the cut out portions 14 are suitably arranged and of sufficient extent, the scallops adjacent the areas from which the protuberances 15 are formed will be utilized in the first drawing 25 operation and thereafter the edges of the strip 12 will form straight lines as indicated in Figure IV.

After eight protuberances 15 have been formed in the metal strip 12, the strip is fed to a second 30 die drawing machine adapted to simultaneously shape and size the protuberances 15 as indicated at 16 in Figures III and IV. Thereafter the strip is fed successively to other die drawing machines, which shape and size the protuberances 16 as 35 indicated at 17, 18, 19, 20 and 21 in Figures III and IV. At the time the last operation, which consists in shaping and sizing the spoke 21, is performed the base of the spoke including the adjacent portion of the flat strip of metal 12 is 40 formed to the arc of the completed spoke spider, as indicated at 22.

The strip of metal 12 consisting of eight spoke members 21 with their bases curved as indicated at 22, all of which is shown in Figure III, is 45 bent into hoop formation, as indicated in Figure V. In forming the spoke spider 10 from the strip of metal 12 including the spoke members 21, all of the bending, or the shaping, of the strip occurs between the spoke members 21 in the area 50 indicated at 23 in Figures III and IV. In this manner the spoke members 21 are not in any way distorted at the time the strip is bent into the hoop formation shown in Figure V.

The opposite ends 24 of the strip of metal 12

are preferably secured together after the strip has been bent into hoop formation by welding the same as indicated at 13. The completed spoke spider 10 is assembled in a wheel structure in a 5 manner which will be described presently.

In addition to the preferred method just described for producing the spoke spider 10 the same may be produced in the following manner: The sheet metal utilized in forming the spoke 10 spider may be supplied in rolls or strips longer than the strips 12 shown in Figures I and II. Where this method is utilized the strip of metal is fed to a die drawing machine, not shown, equipped with a series of aligned dies each 10 adapted to produce one of the protuberances shown at 15 to 21 inclusive. As the strip is fed to the machine the first die forms the protuberance 15. The strip is then advanced to the next die which forms the protuberance 16 15 from the protuberance 15. The process is repeated with each of the other dies successively. All of the dies may be operated simultaneously to produce their respective formation. In this manner the metal strip is fed continuously to the machine whereby to produce any desired 20 number of spokes 21 all connected together. The strips of completed spokes may be of any length desired and may be cut into sections to form spoke spiders of the required size by bending 25 the same into hoop formation as previously described.

Where the spoke members 21 are drawn from the metal 12 in the manner just described, or as previously described, the spokes 21 are preferably spaced 3.1416 inches apart whereby the diameter of the completed spoke spider may be varied one or more inches by adding or eliminating one or more spoke members. While in 30 spokes for vehicle wheels the spacing of the spokes would generally be measured in inches, it should be understood that the same result would be obtained by using 3.1416 units of any linear measure desired. This spacing of the 35 spokes is accomplished by properly positioning the dies utilized in drawing the protuberances 15 to 21 inclusive.

While, as shown in Figures III and IV, seven separate die drawing, shaping and sizing operations are utilized in forming the spoke members 21, it should be understood that any suitable 40 number of operations may be utilized depending upon the size and shape of spoke desired; although it has been found that the best 45 results are obtained by utilizing the number specified.

After the spoke spider 10 has been formed by either of the methods heretofore described, the edges of the strip of metal 12 are preferably flanged as indicated at 25 and 26 in Figure VI. 50 This flanging operation may be performed, if desired, before the strip is bent into hoop formation.

Thereafter a rim 27 is seated upon the ends of the spoke members 21 and secured in that position by means of rivets 28 extending through the closed outer extremity of the spokes 21 and the base of the rim 27.

A hub attaching flange 29 is secured to the strip of metal 12 at the base of the spokes 21 after the rim has been secured to the spoke ends. The hub attaching flange is preferably welded to the flange 25 and the axially extending portion of the flange 26 whereby to close the opening into the interior of the spokes 21. In this manner

dirt and moisture are prevented from entering the interior of the spokes. The innermost extremity of the flange 26 forms a circular opening to which a conventional hub cap 30 provided with securing means 31 is removably attached. 5 Suitable openings 32 are formed in the hub attaching flange 29 whereby the same may be connected to a hub 33 by means of conventional securing bolts 34. A brake drum 35 is preferably secured to the hub 33 by means of the securing 10 bolts 34.

From the foregoing description it will be apparent that this invention provides a simple and inexpensive method of producing a durable wheel of light weight embodying a unitary spoke spider 15 formed from a single sheet of metal. While only the preferred forms of the invention have been shown and described it should be understood that the invention is not limited to these forms but is coextensive with the scope of the appended 20 claims.

I claim:

1. The method of producing a unitary spoke spider for vehicle wheels from a single strip of sheet metal which comprises die drawing the 25 metal at spaced intervals to form a plurality of hollow elongated spoke members closed at their outer extremities, bending the strip into hoop form with the spoke members extending radially therefrom, and securing the adjacent ends of 30 the strip of metal together whereby to preserve the hoop formation thereof.

2. The method of producing a spoke spider for vehicle wheels from sheet metal which comprises die drawing the metal to form a plurality of 35 equally spaced complete hollow spoke members, cutting the sheet metal containing the hollow spoke members to the desired length and width, bending the strip of metal thus formed into hoop formation, and securing the ends of 40 the strip together whereby to preserve the hoop formation thereof.

3. The method of producing a unitary spoke spider for vehicle wheels from a single strip of sheet metal which comprises die drawing the 45 metal to form a plurality of equally spaced apart and aligned hollow spoke members, bending the strip into hoop formation with the spoke members extending outwardly along radial lines, and securing the strip in the said hoop formation. 50

4. The method of producing a spoke spider from sheet metal which comprises die drawing the metal at spaced intervals to form a plurality of cylindrical spoke projections, elongating and shaping the said projections in additional dies 55 to form spokes of the desired shape and size, and bending the metal containing the spokes into hoop formation.

5. The method of producing a spoke spider from a strip of sheet metal which comprises 60 forming a plurality of aligned and spaced apart cylindrical projections in the metal by simultaneous die drawing operations, shaping and elongating each of the said projections simultaneously by a series of additional die operations, to 65 form spokes of the desired shape and size, bending the strip into hoop formation, and securing the strip in said hoop formation.

6. The method of producing a unitary spoke spider for vehicle wheels from a single strip of 70 metal which comprises die drawing from a strip of metal a plurality of spoke projections having closed outer extremities adapted to be attached to a rim, and bending the strip into hoop formation with the spokes extending radially outward. 75

7. The method of producing a spoke spider from a strip of metal which comprises die drawing a plurality of spaced apart spoke projections from the metal, shaping the metal at the base of the spoke to the arc of the completed spoke spider, and bending the metal between the spokes whereby the said arc portions form a continuous cylinder.

8. The method of producing a spoke spider from a strip of metal which comprises die drawing a plurality of spaced apart spoke projections from the metal, shaping and elongating the projections to form spokes of the desired shape and size, shaping the base of the spokes simultaneously with the last mentioned operation to the arc of the completed spoke spider, and bending the metal between the spokes whereby the said arc portions form a continuous cylinder.

9. The method of producing a spoke spider for assembly in a vehicle wheel from a single sheet of metal which comprises forming a plurality of spaced apart spoke projections in the metal, bending the strip of metal into hoop formation with the spokes extending radially outward, and forming an inwardly turned flange at one side of the metal strip.

10. The method of producing a spoke spider having a cylindrical nave construction which comprises die drawing a flat strip of metal to form a plurality of spaced apart spoke projections, bending the strip into cylindrical formation with the spokes projecting radially outward, and bending one edge of the strip to form a radially extending flange.

11. The method of producing a spoke spider from sheet metal which comprises die drawing the metal at spaced intervals to form a plurality

of cylindrical projections, shaping and elongating said projections by successive die drawing operations to form complete spokes, and bending the metal from which the spokes project into hoop formation.

12. In the method of producing a spoke spider for vehicle wheels the steps comprising, die drawing a sheet of metal at spaced intervals to form a plurality of hollow elongated spoke members closed at their outer ends, and bending the sheet thus formed into arcuate form with the spoke members extending radially outwardly therefrom.

13. The method of forming a one-piece sheet metal artillery wheel part including spokes integrally joined at corresponding ends, which method comprises striking the spoke portions to extend transversely from the blank sheet and bending the sheet to place the spokes in operative position.

14. The method of forming a one-piece sheet metal artillery wheel part including spokes of hollow section integrally joined at corresponding ends, which method comprises simultaneously pre-forming the blank to shape the spokes and to place them in inoperative position on the thus pre-formed blank and subsequently bending the blank to place the spokes in operative position.

15. The method of forming a one-piece sheet metal artillery wheel part which comprises simultaneously pre-forming the blank to provide tubular spokes and to place the spokes in inoperative position on the blank and subsequently bending the blank to place the spokes in operative position.

JOHN T. TRUMBLE.
